PROSTHETIC APPLIANCE

Johann W. Bach, Germaniaplatz 267,
Essen-Borbeck, Germany

Filed May 19, 1961, Ser. No. 121,275

Claims priority, application Germany July 8, 1960
12 Claims. (Cl. 3—21)

My present invention relates to a prosthetic appliance for artificial limbs, and more particularly to an artificial member (e.g. thigh or shank) forming part of such appliance.

Some artificial limbs at present in the market, designed to afford a more flexible fit than those with rigid wooden or plastic sockets, are provided with leather sheaths or with padding usually made of foam rubber; they have, however, the disadvantage of forming an airtight connection around the stump of the amputated extremity, thus causing perspiration and often the appearance of boils and heat rashes. The blood circulation may also be disturbed by conventional appliances which are so rigid as to inhibit any movement of the stump muscles.

It is, therefore, an object of my present invention to provide an artificial limb member which assures satisfactory ventilation of the stump.

It is a further object of the present invention to provide a prosthetic member of sufficient elasticity to exert, during normal use, an invigorating massaging effect upon the stump and to stimulate its blood circulation.

It is another object of this invention to provide an artificial limb member of light weight and flexible construction resistant to wear and damage when in use.

A still further object of the present invention is to provide a prosthetic member whose length can be conveniently adjusted within certain limits.

In accordance with the feature of the present invention, the annular socket portion and the other, lower extremity (i.e. the part terminating in a knee or ankle) of the artificial member are interconnected by preferably outwardly arched spacer bars or staves of strong elastic material, e.g. a light-weight metal such as aluminum or one of its alloys, prestressed to a certain extent by a series of flexible links holding the two extremities together and surrounding the inserted stump so as to shield it from contact with the spacer bars while affording access to the surrounding air.

According to a preferred embodiment of the present invention, the flexible links form a tubular array between two annular holders, one on the bottom part of the socket portion and one on the upper part of the lower portion. The spacer bars are advantageously joined with the holders in a single sleeve-type unit integral with or suitably attached to the two extremities.

The flexible links are preferably constituted by strands of metal or plastic inserted in protective sheaths at least 5 mm. in diameter, so as not to cut into the tissue upon coming into contact with the skin of the wearer. The elastic deformability of the spacer bars results in a light massaging of the stump when the appliance is put to its intended use. I prefer to employ as the links different portions of a single composite cable (or a small number of such cables) anchored to the holders and continuously wound back and forth between them.

If either or each holder is adjustably mounted on the respective extremity of the prosthetic member, it may be reset from time to time to compensate for creep of the flexible link material (especially in the case of plastic filaments) and/or to adapt the length of the member to the specific needs of the wearer.

The above and other features, advantages and objects of the invention will become more readily apparent from

2

the following detailed description, given in conjunction with the appended drawing in which:

FIG. 1 is an overall perspective view of a prosthetic member according to the present invention, designed as a thigh prosthesis;

FIG. 2 is a longitudinal sectional view of the thigh prosthesis shown in FIG. 1;

FIG. 3 is a perspective view of the sleeve portion of the prosthesis of FIGS. 1 and 2, forming an intermediate unit between its extremities;

FIGS. 4 and 5 are respectively a cross-sectional view and a longitudinal sectional view of the unit illustrated in FIG. 3; and

FIG. 6 shows a cross-section through the cable used in the unit of FIGS. 3-5, drawn to an enlarged scale.

As shown in FIGS. 1 and 2, the artificial limb comprises a socket portion 1, a sleeve 2 and a lower extremity 3. The socket 1 is appropriately shaped to accommodate the upper part of the stump to be inserted through its outwardly flared upper end which may be additionally fastened to the body of the wearer by suitable means not illustrated. The lower extremity 3 is upwardly concave and is externally split into sections traversed by a shaft 3a by which it can be hinged to a complementary part, not shown, of a knee joint whose structural details are not pertinent to the present invention. A shoulder 15 on the lower end of the socket portion 1 and a shoulder 16 on the upper edge of the lower extremity 3 support holder rings 5 and 6 which are firmly cemented to these extremities, e.g. by an epoxy resin, or press-fitted to the shoulders. Removable annular shims 17 on the shoulders 15, 16 may be used to change the length of the artificial limb when necessary. The holder rings are spaced apart by staves 7, preferably made of metal, which are rigidly joined to the holder rings. The staves are bent outwardly and prestressed by a cable 4 which, as shown in FIG. 2, passes back and forth between the rings 5 and 6 along their whole inner peripheries and is stretched to a certain extent to assure proper stressing of the barrel-shaped sleeve unit 2 formed by the rings 5 and 6 with the staves 7 and the cable 4. As shown in FIG. 6, the cable 4 is constituted by filaments 8, preferably made of plastic, and protected by a flexible sheath 9, preferably also of plastic. The metallic portions 5, 6, 7 of sleeve 2 along with the external areas of the socket portion 1 and the lower extremity 3 are protected by a flexible varnish or plastic coating 14.

The sleeve 2 is shown in greater detail in FIGS. 3, 4 and 5, in which the holder rings 5, 6 are shown spaced apart by four outwardly bent staves 7 fastened to the rings by rivets 18. The cable 4 is secured to the inner peripheries of the rings 5, 6 by threads 12 and 13. Thread 12 passes successively through each upper loop of the cable 4 and a set of openings 11 in the upper holder ring 5, while thread 13 passes in a similar manner successively through each lower loop of the cable 4 and a set of openings 10 in the lower holder ring 6. The slight spacing between the individual longitudinal reaches of the cable 4 assures a satisfactory ventilation of the interior of the sleeve 2.

The length of the artificial limb member, preset by the initial tension of the cable 4, may vary on account of a sagging of the filaments 8 with resultant flattening of the staves 7 accompanied by an increase in the distance between the socket portion 1 and the lower extremity 3. To compensate for this change in length it may be necessary to withdraw either or both rings 5, 6 from their respective shoulders 15, 16 and to remove as many of the shims 17 as is required, whereupon the seating areas of the holder rings will again be cemented or press-fitted to their respective extremities 1 and 3; in like manner additional shims may be inserted if lengthening of the limb is desired. The

staves 7 must, of course, be strong enough to support the body weight of the amputee even in their most highly flexed position without letting the end of the stump touch the hollowed-out limb portion 3.

Various modifications may suggest themselves to those skilled in the art, especially with respect to the connection of the holder rings with the staves or to the fastening of these rings to the extremities 1 and 3, without departing from the spirit of the present invention within the scope of the appended claims.

I claim:

1. In an artificial limb for a prosthetic appliance, in combination, a pair of generally annular members axially spaced apart, a subular array of flexible links interconnecting said members under tension, and a plurality of curved resilient staves substantially more rigid than said links inserted at angularly spaced locations between said links and firmly secured to said members at opposite ends.

2. The combination according to claim 1 wherein said links comprise at least one cable wound back and forth between said members.

3. The combination according to claim 1 wherein said staves are bent outwardly beyond the periphery of said array.

4. In a prosthetic appliance, in combination, a socket element adapted to receive a stump, and a sleeve body comprising a pair of generally annular members axially spaced apart, a tubular array of flexible links interconnecting said members under tension, and a plurality of curved resilient staves substantially more rigid than said links inserted at angularly spaced locations between said links, one of said members being rigidly joined with said socket element.

5. The combination according to claim 4, further comprising another element forming an extremity opposite said socket element while being rigidly joined with the other of said members.

6. The combination according to claim 5 wherein said elements are provided with generally annular shoulders surrounded by said members, said staves being secured to said members externally of the latter.

7. The combination according to claim 6, further comprising a protective outer coating extending over said elements and said staves.

8. In a prosthetic appliance, in combination, a socket

5 element adapted to receive a stump, a sleeve body comprising a pair of generally annular members axially spaced apart, a tubular array of flexible links interconnecting said members under tension, and a plurality of curved resilient staves substantially more rigid than said links inserted at angularly spaced locations between said links, and means forming an adjustable connection between one of said members and said socket element.

9. In a prosthetic appliance, in combination, a socket element adapted to receive a stump, a sleeve body comprising a pair of generally annular members axially spaced apart, a tubular array of flexible links interconnecting said members under tension, and a plurality of curved resilient staves substantially more rigid than said links inserted at angularly spaced locations between said links, another element forming an extremity opposite said socket element, first connection means rigidly joining one of said members with said socket element, and second connection means rigidly joining the other of said members with said other element, at least one of said connection means being adjustable.

10. The combination according to claim 9 wherein said adjustable connection means includes removable spacer means between one of said members and the associated element.

11. An artificial limb for a prosthetic appliance, comprising a pair of generally annular members axially spaced apart, a plurality of curved resilient staves spacedly disposed about said members and joined thereto at respective ends, thereby forming a sleeve with lateral gaps, and flexible tie means anchored to said members under tension and comprising at least one cable wound back and forth therebetween in a plurality of substantially parallel passes extending within each of said gaps in the direction of said staves, said tie means maintaining said staves under flexural stress, said cable including a plurality of filaments and a common sheath enclosing said filaments.

12. A limb according to claim 11 wherein said filaments and said sheath consist of plastic material.
